UNITED STATES PATENT OFFICE.

WILLIAM STODDARD, OF HINGHAM, MASSACHUSETTS.

FOLDING BEDSTEAD.

Specification of Letters Patent No. 12,656, dated April 3, 1855.

To all whom it may concern:

Be it known that I, WILLIAM STODDARD, of Hingham, in the county of Plymouth and Commonwealth of Massachusetts, have 5 invented a new and useful Extension-Bedstead; and I hereby declare that the following is a full, clear, and exact description of its construction and use, reference being had to the accompanying drawings and letters 10 marked thereon.

Of the said drawings Figure 1, denotes a plan. Fig. 2, a side elevation. Fig. 3, a transverse and vertical section at A, B, showing the slats and shoulders on them. 15 The nature of my invention consists of an extension bedstead so constructed and arranged as to be folded together, and in that position answer for a sofa by removing the foot board, and so that the bedstead can be 20 extended so as to answer all the purposes of a bedstead, the sofa back and head board being one and the same thing, the foot board being turned under the cushion of the sofa when the bedstead is folded together 25 and used as a sofa.

To explain the method of constructing my invention and carrying it out I will describe the same as follows: I construct four posts of wood as seen at A, A, two of which 30 I attach to each of the cross rails, or head and foot rails B, B, and above these cross rails I attach a head and foot board to each of the two posts respectively at each end of the bedstead. I now connect the head and 35 foot portions of the bedstead together by the extension rails C, C, these being constructed of several pieces of wood and are connected together by iron hinges D, D, or other equivalents so that they will fold together to answer the purpose of a sofa, and 40

also so as to be easily removed from houses in case of fire, it being folded so as to pass through any ordinary door. It will be understood that the end of each of these extension rails is connected to each of the 45 posts by a hinge so as it will turn to allow these rails to be drawn out and folded together at pleasure. At E, can be seen the slats which support the bedding, and they are sustained on the tops of the extension 50 rails when the bedstead is extended. These slats answer the double purpose to support the bedding and to keep the extension rails straight by means of the hooks G, and shoulders F at the ends of these slats, 55 which pass down by the edges of these extension rails. These slats are connected together by tape, leather, or any flexible substance as seen at H, and when the bedstead is drawn out, the ends of these strings 60 are tied to the foot board, so as to keep the slats in the right position when the bed is used.

Having thus described my extension bedstead, I claim as new and useful— 65

The making the side rails of bedsteads, in sections hinged together and also to the head and foot posts, so that they will fold together substantially as specified, in combination with the slats which support the bedding, which slats are so constructed, and provided with pins or projections near the ends of them as to brace or hold the folding rails firm, when the bedstead is extended, 70 essentially in the manner and for the purposes set forth. 75

WILLIAM STODDARD.
